CLAIM

The ornamental design for a shoe midsole, as shown and described.

DESCRIPTION

FIG. 1 is a first side rear perspective view of a shoe midsole showing my new design in which at least a portion of the shoe midsole is shown as having a transparent or translucent surface;

FIG. 2 is a second side rear perspective view thereof; and, FIG. 3 is a first side view thereof.

The even-length broken lines are directed to environment, represent unclaimed subject matter, and form no part of the claimed design.

1 Claim, 3 Drawing Sheets
